PICKUP HOOK FOR BROKEN RODS

William D. Osborn, Los Angeles, Calif.

Application October 11, 1939, Serial No. 298,983

1 Claim. (Cl. 294—19)

My invention relates to a hook, particularly designed for engaging and removing broken or disjointed rods, such as are used in connection with sewer and other pipe cleaning apparatus, also the sucker or pump rods used in connection with deep well pumps, and, the principal objects of my invention, are to generally improve upon and simplify the construction of the existing forms of broken and disjointed rod pick-up hooks and devices and, to provide a pick-up hook or device that is formed from a single piece of material and which when rotated in a sewer, pipe line, well casing, or the like, will be highly effective in engaging a broken or disjointed rod and automatically clamping the same so that it may be readily withdrawn from the sewer pipe or casing.

A further object of my invention is, to provide a rod pick-up hook or device that is especially designed for use in engaging, picking up, and removing rods having their ends detachably connected by joints and the parts of which joints are somewhat larger in diameter than the connected rods.

A further object of my invention is, to provide a rod pick-up device that is practically automatic in its action of engaging a broken or uncoupled rod and positioning the same so as to effect a connection between a looped portion of the tool and the coupling or joint members between the rod sections, so that the broken or uncoupled rod may be readily removed from the sewer pipe or other line as the tool is withdrawn therefrom.

With the foregoing and other objects in view, my invention consists in certain novel features of construction and arrangement of parts that will be hereinafter more fully described and claimed and illustrated in the accompanying drawing in which:

Fig. 1 is a sectional view taken lengthwise through a duct such as a sewer pipe and showing the pick-up tool positioned for use therein.

Fig. 2 is an enlarged top plan view of the rod engaging end of the pick-up tool.

Fig. 3 is a bottom plan view of the rod engaging end of the tool.

Fig. 4 is an enlarged cross section taken approximately on the line 4—4 of Fig. 1.

Fig. 5 is an enlarged plan view of the end of the curved arm of the pick-up device.

Fig. 6 is a section taken on the line 6—6 of Fig. 5.

Referring by numerals to the accompanying drawing which illustrates a preferred embodiment of my invention, 10 designates a metal rod which may be of any convenient length, for in-

stance, three or four feet, and mounted on the rear end of said rod is a coupling member 11 that is adapted to engage a complementary member 12 that is formed on the end of a rod section that forms a part of the rod string that is used for inserting the pick-up tool in the sewer or other pipe line and for manipulating said tool after it has reached the broken or disjointed portion of the rod that is to be removed.

10 The forward portion of rod 10 terminates in an arm 13 that has the general shape of the segment of a helix. The end of this arm is widened slightly and made wedge-shape lengthwise of the arm so as to form a substantially chisel-shaped member 14 and, the forward sharp edge thereof being curved forwardly from one side to the other as designated by 15.

15 The end of the curved arm 13 opposite the chisel-shaped end 14 is curved inwardly toward 20 the forward end of the straight body portion of the rod 10 as designated by 16 and, this curved portion gradually approaches the axis of the straight body portion of the rod 10 so as to provide a relatively small open loop 17. This loop 25 occupies a position substantially at right angles to the axis of the straight body portion 10 of the tool and, the opening in said loop is slightly larger than the diameter of the rods used in connection with sewer and other pipe line cleaning apparatus and, said loop being somewhat 30 smaller than the diameter of the couplings between the rod sections.

35 As a result of this construction, the open loop 17 provides a shoulder against which a rod coupling rests when a broken or disjointed rod has been picked up and is being removed from the sewer or other pipe line.

40 In the use of my improved rod pick-up tool, the latter detachably connected by means of the coupling members 11 and 12 to the end of a string of rods is moved into the sewer pipe or other pipe line in which the broken or disjointed rod is located and the tool is moved to a position one or two joints past the broken end of the rod 45 or the disconnected joint and, the tool is now rotated by the application of suitable power to the rod string that is connected to said tool.

45 As a result of this rotation, the chisel end of the curved arm rides around the inner face of the sewer pipe or other conduit and, as such rotary motion continues, the end of the arm 13 passes beneath the broken or disjointed rod as illustrated in Fig. 4 and further rotary movement of the tool will cause the engaged rod to ride 50 along the curved portions 13 and 16 of the tool 55 along the curved portions 13 and 16 of the tool

and said rod will finally pass into the open loop 17.

Retractive movement is now imparted to the rod string connected to the tool and, when the loop 17 engages the joint between two of the sections of the broken rod, said joint will bear against the shoulder formed by the loop 17 and, as the tool and the broken or disconnected rod are now practically locked to each other, the broken or disjoined rod may be conveniently withdrawn from the sewer or other pipe line with the tool.

Among the particularly advantageous features of my invention are, the coupling engaging loop 17 that is disposed at right angles to the axis of the straight body portion of the tool, thereby forming an effective shoulder for engaging a coupling in the rod string that is to be removed from a sewer or the like and, the curved arms 13 and 16 which during the rotation of the tool automatically cause the engaged rod to pass into the loop 17, thus positioning said rod so that one of the couplings thereof will engage against the loop as the tool is drawn longitudinally relative to the broken or disjoined rod.

Thus it will be seen that I have provided a pick-up tool for broken or disjoined rods that is relatively simple in construction, inexpensive of

manufacture and very effective in performing the functions for which it is intended.

It will be understood that minor changes in the size, form and construction of the various parts of my improved pick-up hook for broken rods, may be made and substituted for those herein shown and described, without departing from the spirit of my invention, the scope of which is set forth in the appended claim.

I claim as my invention:

A pick-up hook for broken jointed rods or the like having joints of greater diameter than that of said rods, comprising an elongated straight and solid shank having front and rear ends, the front end of said shank being formed to provide an open loop having co-planar portions at right angles to said shank, the free end of said loop being extended forwardly thereof in the form of an outwardly diverging helix having an arc of substantially 180°, the internal diameter of said open loop being slightly greater than that of a rod and less than that of a joint, whereby said loop is adapted to freely receive a rod at points intermediate of the joints and be retracted along the rod to bring a joint into engagement with said co-planar portions of said loop.

WILLIAM D. OSBORN.
